UNITED STATES PATENT OFFICE.

CARL A. JOERISSEN, OF WASHINGTON, DISTRICT OF COLUMBIA, ASSIGNOR TO UNDERWOOD TYPEWRITER COMPANY, OF NEW YORK, N. Y., A CORPORATION OF NEW JERSEY.

TYPE-WRITING MACHINE.

No. 858,655.

Specification of Letters Patent.

Patented July 2, 1907.

Application filed May 25, 1907. Serial No. 375,571.

To all whom it may concern:

Be it known that I, CARL A. JOERISSEN, a citizen of the United States, residing in the city of Washington, District of Columbia, have invented certain new and useful Improvements in Type-Writing Machines, of which the following is a specification.

This invention relates to card-holders adapted to be attached to the cylindrical platens of typewriting machines, and particularly to means whereby to facilitate the detachment of the card-holders. Devices of this class usually comprise a strip of springy metal extending along the platen, and provided with suitable card holding means, such as a series of tongues to catch over the leading edge of the card; and at its ends said strip is usually bent down to form arms, which are forked to bestride the hub of the platen, such forked arms being provided with claws to catch over the heads of the platen and secure the card-holder thereto.

The object of the present invention is to avoid the difficulty and annoyance heretofore experienced in releasing the claws and manipulating the card holder.

In the accompanying drawings, Figure 1 is a front elevation of a typewriter-platen with my improved device applied thereto. Fig. 2 is an end view of the same. Fig. 3 is a view of the left-hand portion of a platen, showing the manner of releasing the device from the head of the platen. Fig. 4 is a view similar to Fig. 3, but showing the device about to be lifted from the platen. Fig. 5 is a perspective view of the improved card holder. Fig. 6 is a view of the left hand portion of the improved card-holder showing a modification thereof.

The card-holder comprises a strip 1 of springy metal extending the length of the platen and provided with a series of tongues 2 for firmly holding the leading edge of a card. At each end the metal strip 1 is bent down to form arms 3, which are forked, as at 4, to bestride the hub 5 of the platen A of a typewriting machine. The forks have at their free ends claws 6 to catch over the heads 7 of the platen.

I provide at each end of the card-holder a releasing device in the form of a rigid forked arm 9 of sheet metal, and formed to correspond substantially with the forked end 3, and secured at its lower extremity to said forked end in any convenient manner, as by soldering or riveting. From its point of attachment said releasing arm extends outwardly, as at 10, and then upwardly, as at 11. At its upper or free end 12, said releasing arm is bent inwardly toward the card-holding strip; and in the present instance is shown as bent partly around the corner formed at the junction of said strip and its forked end. Said end 12 is also hooked outwardly to form a finger-piece 13 for lifting the card-holder from the platen.

When it is desired to detach the card-holder, a slight pressure inwardly and toward the platen is applied by the fingers to the hooked portions 13. The releasing arms 9 being constructed of rigid metal, while the forked arms of the card-holder are constructed of flexible metal, such pressure exerted on the arms 9 will flex the forked ends 2 and 3 above the point of attachment of the arms 9, and the claws 6 are thereby disengaged from the head of the platen, as shown in Fig. 3; and then by a slight upward pull upon the hooks 13, the card-holder is easily lifted from the platen, as shown in Fig. 4.

In Fig. 6 is shown a modification of the outwardly hooked finger-piece 13, for lifting the card-holder from the platen.

Having thus described my invention, I claim:

1. A card-holder comprising a card-holding strip to lie along the platen of a typewriting machine and having flexible depending ends which are forked to bestride the platen-hubs and which have claws to catch over the platen-heads, one of said ends having a releasing device in the form of a forked arm attached at its lower extremity to the forked portions of said end and extending outwardly and upwardly from its point of attachment, and at its upper end bent inwardly partly around the corner, formed at the junction of said strip and said end, and then hooked outwardly to form a finger-piece for lifting the card-holder from the platen; said arm being sufficiently rigid not to bend when pressed toward the platen for releasing the claws. 70

2. A card-holder comprising a card-holding strip to lie along the platen of a typewriting machine and having flexible depending ends which are forked to bestride the platen-hubs and which have claws to catch over the platen-heads, releasing devices in the form of forked arms, one of said devices being attached at its lower extremity to the forked portions of each of said ends, and extending outwardly and upwardly from said point of attachment, and at its upper end hooked to form a finger-piece for lifting the card-holder from the platen; said arms being sufficiently rigid not to bend when pressed toward each other to release the claws. 85

3. A card-holder comprising a card-holding strip to lie along the platen of a typewriting machine, having flexible depending ends which have claws to catch over the platen heads, an arm attached to each of such flexible ends at its lower extremity, and each arm extending outwardly and upwardly from its point of attachment and at its upper end provided with a finger-piece. 100

4. A card-holder comprising a card-holding strip, to lie along the platen of a typewriting machine, having flexible depending ends which are forked to bestride the platen-hubs and which have claws to catch over the platen-heads, rigid sheet-metal arms one of which is secured to each forked end and formed to correspond substantially with such forked end, each arm being offset near the point of attachment and extending upwardly, and at the upper and free end bent inwardly toward said strip, and hooked to form a finger-piece. 105
